San Antonio, Tex. 78230

Original design application May 18, 1972, Ser. No.
254,834, now Patent No. 231,902. Divided and this
application Dec. 17, 1973, Ser. No. 425,092

Term of patent 14 years

Int. Cl. D8—08

U.S. Cl. D8—266

The figure is a perspective view of a strip of staples. The broken line illustration of the printed matter is merely representative of the type of indicia that may appear on the staples. The side opposite that shown is identical to the side that is shown. The underneath of the top of the staples is a flat surface.

This application is a division of application Ser. No. 254,834, filed May 18, 1972, now Pat. D. 231,902, dated June 25, 1974.

I claim:

The ornamental design for a strip of staples, as shown and described.
